CIGARETTE PACKAGE

Arlie Leon Booth, Miami, Fla.

Application October 11, 1938, Serial No. 234,446

1 Claim. (Cl. 229—51)

This invention aims to provide a new and improved cigarette package, the construction being such that the opening of the package will be facilitated, and the extraction of each cigarette being made easy. Another object of the invention is so to construct the package that, until it is opened, cigarettes will be adequately protected, and will not be subject to deterioration by exposure.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawing:

Fig. 1 shows in perspective, a cigarette package constructed in accordance with the invention;

Fig. 2 is an elevation;

Fig. 3 is a side elevation, a portion of the package having been removed, and there being a full number of cigarettes in the package;

Fig. 4 is a top plan of the structure shown in Fig. 3;

Fig. 5 is a view similar to Fig. 3 but illustrating how the device operates as the cigarettes are removed from the package;

Fig. 6 is a top plan of the article shown in Fig. 5;

Fig. 7 is a section on the line 7—7 of Fig. 2;

Fig. 8 is a diagrammatic top plan showing a modification.

In the drawing, the numeral 1 marks a receptacle, made in the usual way, and composed, as shown in Fig. 7, of a plurality of layers of paper, tinfoil and the like, marked by the numeral 2.

The receptacle 1 has a continuous line of perforations 3 defining a completely removable portion in the package.

The line of perforations 3 is continuous and extends transversely of the top 4 of the package, as shown at 5. The line of perforations extends downwardly as shown at 6, at any desired angle with respect to the top 4 of the package, along the sides 7 of the package, and across one end 8 of the package, below the top 4 of the package, in the form of a downwardly extended V, as indicated at 9.

Owing to the fact that the receptacle 1 has the continuous line of perforations above referred to, it will be obvious that there is formed a completely removable portion 10, which may be detached by tearing it off along the perforations.

Comparing Figs. 3 and 5, it will be noted that, as the cigarettes are removed from the package, the cigarettes that remain in it tend to gravitate downwardly along the parts 6 of the perforations and rest in the V of part 9. Figures 5 and 6 indicate that, owing to the construction above referred to, one cigarette is always presented prominently for withdrawal, that cigarette being located in the lowermost part of the V 9. As fast as the cigarettes are removed from the bottom of the V, other cigarettes slide downwardly toward the lowermost portion of the V, to replace the cigarette that has been removed.

If desired, the receptacle may be enclosed within the usual covering 12, made of Cellophane or the like.

The perforating can be done in the constituent material of the package, before the package is put together, there being no additional expense to the manufacturer other than for the necessary perforating machine.

The device is simple in construction. The removable section 10 is readily detached, and there are no hinge portions leaving a connected and cumbersome closure part, there being no occasion for such a closure part, since the cigarettes are used up so promptly that a closing of the package is not necessary.

In Fig. 8, parts hereinbefore described have been designated by numerals already used, with the suffix "a." In this form, the portion 5a of the perforations is located closer to the surface 3a of the package than is the corresponding part 5 of Fig. 1. As a consequence of this construction, the package is not opened so completely at the top. Fewer cigarettes are exposed and the likelihood that they will be bent over or broken is reduced.

Having thus described the invention, what is claimed is:

A cigarette package comprising a receptacle having a continuous line of perforations defining a completely removable portion in the receptacle, the line of perforations extending transversely of the top of the receptacle, along the sides of the receptacle, in downwardly slanting lines, and across one completely closed end of the receptacle, below the top of the receptacle, in the form of a downwardly extending V, the edges of which extend upwardly to the lower ends of said downwardly slanting lines.

ARLIE L. BOOTH.
